UNITED STATES PATENT OFFICE.

JOHN E. HARNER, OF SPRINGFIELD, OHIO, ASSIGNOR TO THE BUCKEYE INCUBATOR COMPANY, OF SPRINGFIELD, OHIO, A CORPORATION OF OHIO.

HOVER.

Specification of Letters Patent. Patented Mar. 23, 1920.

1,334,368.

Application filed May 15, 1919. Serial No. 297,419.

To all whom it may concern:

Be it known that I, JOHN E. HARNER, a citizen of the United States, residing at Springfield, in the county of Clark and State of Ohio, have invented certain new and useful Improvements in Hovers, of which the following is a specification, reference being had therein to the accompanying drawings.

10 My invention relates to hovers and more particularly to hovers employing an oil burning lamp.

The object of my invention is to provide an improved hover in which the supply of heat is conserved and directed to give the 15 most efficient service.

A further object of my invention is to supply an improved hover in which I provide means to prevent its loss by fire.

20 I have found that when the lamp is burning it generates a gas in the bowl greater in quantity than is consumed by the burner and in the ordinary form of hover this excess escapes into the heating chamber. Here 25 it accumulates and when it has attained a certain degree of heat will ignite and destroy the hover.

To overcome this I have devised means to prevent the entrance of the gas into the heating chamber by venting it to the atmosphere 30 outside the hover.

My invention is adapted to all forms of hovers employing lamps but it is particularly adapted for use in the portable type 35 of hover that is self-contained and can be lifted and moved from place to place.

In this type of hover it is common to provide a vent pipe extending from near the bottom of the heating chamber through 40 the cover to the atmosphere outside the hover. While this arrangement aids radiation through the bottom of the heating chamber which forms the top of the hover chamber, it causes the accumulation 45 of gases subject to ignition and destruction of the hover as hereinbefore pointed out.

My invention consists of the constructions and combinations hereinafter more fully described and set forth in the claims.

50 In the accompanying drawings which form a part of this specification Figure 1 is a sectional view of a hover circular in form embodying my invention. Fig. 2 is a cross-section on the line 2-2 of Fig. 1 and Fig.

3 is a fragment of a side elevation with the door of the hover removed.

Referring to the drawings 1 represents the side walls and 2 the upper wall or cover of a hover within which there is disposed 60 a heating chamber 3; and a lamp chamber 4 having side walls 5 and a bottom 6 opens into said heating chamber through the bottom 7 of said chamber.

A space 8 between the outer walls of the 65 hover and the walls 9 and 10 of the heating chamber is closed by the extensions 7^a and 9^a forming a dead air chamber that acts as a non-conductor to keep out the cold and retain the heat within the hover.

The bottom 7 of the heating chamber together with a curtain 11 hung from the lower edge of the side walls 1 forms the hover or brooder chamber; and the hover is supported upon legs 12 disposed at intervals about the hover.

The lamp chamber is provided with a partition 13 having a central opening through which the neck 14 of the burner 15 of the lamp bowl 16 projects.

A door 17 hinged at 18 closes upon the frame 17^a of an opening into the lamp chamber and a slot 19 in the partition 13 permits of the introduction of the lamp into the chamber; and a slide 20 having arms 21 pivoted at their respective ends to said slide and partition, shown by the dotted lines in Fig. 2 in open position and by the full lines in closed position, forms the means of closing the slot in the partition. A bar 22 90 riveted to the partition forms a groove 23 in which the edge of the slide moves.

The lamp bowl is provided with a vent shown in the form of a tube with an inlet 24 from the neck of the lamp burner and an outlet 25 into the lamp bowl inclosure; and from this inclosure a pipe 26 leads to the atmosphere outside the hover. Thus it will be seen the excess gases generated in the lamp bowl are prevented from entering the 100 heating chamber and are vented to the atmosphere outside the hover.

A vent pipe 27 extends from near the floor of the heating chamber through the top of the hover to the atmosphere and a 105 screen opening 28 in the door of the lamp chamber admits fresh air to circulate through said chamber and pass out through said pipe; and an opening 29 in the lamp chamber wall is provided for the escape of 110

foul air from the brooder or hover chamber. The lamp chimney 30 and the door 17 are provided with mica covered peep holes 31 through which the flame of the wick 32 may be observed.

A screened opening 33 in the door 17 admits a current of air to the lamp bowl inclosure to keep the bowl cool and carry the gases off through the pipe 26.

10 Having thus described my invention I claim:

1. In a hover the combination with a lamp chamber having a partition forming a separate inclosure, said chamber and inclosure each having separate outlets to the atmosphere outside of said hover, of a lamp having its burner in said chamber above said partition and its bowl in said inclosure below said partition, said bowl having a vent into said inclosure and means to permit the insertion and removal of said lamp.

2. In a lamp heated hover having an outer casing the combination of a heating chamber in said casing having an outlet to the atmosphere outside of said casing and a lamp chamber opening into said heating chamber, said lamp chamber having a partition forming a separate inclosure having an

outlet to the atmosphere outside of said casing and a lamp having its burner in said lamp chamber upon one side of said partition and its bowl in said inclosure upon the other side of said partition, said bowl having a vent opening into said inclosure.

3. In a lamp heated hover having an outer casing, the combination of a heating chamber in said casing having an outlet extending from near the bottom of said chamber to the atmosphere outside of said casing and a lamp chamber opening into said heating chamber, said lamp chamber having a partition forming a separate inclosure having an outlet to the atmosphere outside of said casing and a lamp having its burner in said lamp chamber upon one side of said partition and its bowl in said inclosure upon the other side of said partition, said bowl having a vent opening into said inclosure.

In testimony whereof I have hereunto affixed my signature in the presence of two witnesses.

JOHN E. HARNER.
